PRINTING DEVICE

Frederick Samuel Rowe, Bloomfield, N. J., assignor to Westinghouse Electric & Manufacturing Company, East Pittsburgh, Pa., a corporation of Pennsylvania

Application November 30, 1938, Serial No. 243,113

9 Claims. (Cl. 101—379)

This invention relates to mechanism for printing or etching insignias on glass devices, such as lamp bulbs, and more particularly to an improved form of stamp and stamp holder for that purpose.

One of the principal objects of my invention, generally considered, is the provision of an improved stamp and holder for printing or etching lamp bulbs and similar glass devices.

Another object of my invention is the provision of a more satisfactory method of holding the stamp used in etching or printing glass devices, such as incandescent electric lamps.

A further object of my invention is the provision of a holder for lamp etching or printing stamps, comprising a body having a threaded extension for connection with operating means, a backing member, a rubber pad, and a sleeve or cap threaded to the body member and having an inwardly extending peripheral flange for engaging the outer edge portion of the stamp proper and holding it in adjustable engagement with the pad and backing member, said backing member presenting a curvature to the pad approximately corresponding with that of the surface to be printed or etched, and the adjustment of the threaded sleeve allowing for variation in the curvature of the stamp proper in order to provide for accurate etching or printing of the lamp bulb or other article.

A still further object of my invention is the reduction in the cost of stamping facilities for printing or etching lamp bulbs, involving the provision of interchangeability between the stamp holders and stamps, and the elimination of cementing the stamp proper to the holder whereby one holder may serve for a large number of stamps.

An additional object of my invention is a holder for rubber stamps used for printing or etching lamp bulbs and similar devices, in which the stamp proper is protected from the action of the inking rollers by a peripheral flange portion on the sleeve which clamps it to the holder or actuating device.

Other objects and advantages of the invention, relating to the particular arrangement and construction of the various parts, will become apparent as the description proceeds.

Referring to the drawing illustrating my invention:

Figure 1 is a fragmentary vertical sectional view showing a stamp embodying my invention and associated machinery at the point in the process where a monogram or other character is being printed on the inside of a lamp bulb.

Figure 2 is a similar view of the machinery shown in Figure 1, in a position where the lamp bulb has been removed, and the stamp is being re-inked preparatory to printing another bulb.

Figure 3 is a face or plan view of a form of stamp and its associated holder embodying my invention.

Figure 4 is a partial elevational and partial axial sectional view of the stamp and holder shown in Figure 3.

Figure 5 is a side or edge view of the stamp proper shown in Figure 4.

Figure 6 is a view corresponding to Figure 4, but showing a modification.

Referring to the drawing in detail, like parts being designated by like reference characters, and first considering the embodiment of my invention illustrated in Figures 3, 4, and 5, there is shown a rubber stamp proper 11 comprising a printing or stamping face 12 which, in the present embodiment, is formed to print the characters "Mazda, 1000 L, 6.6 A, W," all enclosed in circles and arranged as a monogram. The portion 12 is on a thicker central body 13 from which extends a relatively thin peripheral flange 14.

The stamp holder 15 comprises a body or securing element 16 involving a threaded extension 17, carrying a nut 18, and adapted to fit an actuating device which will be subsequently described.

The body portion 16 receives a backing element 19 which, in the present embodiment, telescopes with flange 21 on the body portion 16 and is held in place by means of a set screw 22. The outer surface of the backing member 19, in the present embodiment, is shown at 23 as spherically convex, because it is particularly adapted for use with a holder 15 for printing on spherically concave surfaces.

Normally engaging the surface 23 of the backing member 19 is a resilient pad 24, desirably formed of sponge rubber, on which rests the stamp proper 11, and all three members are held assembled with the body member 16 by the sleeve 25 threaded to said body member, as indicated at 26, and having an inwardly extending peripheral flange 27 which clamps over the flange 14 of the stamp proper 11, and holds it, the pad 24, backing member 19 and body element 16 in assembled relation, exerting the proper amount of pressure on the pad 24 and stamp 11, in order to bend the latter from a normally flat condition to the desired convex shape for properly printing on a concave surface, such as the inner surface of the glass forming the lamp bulb 28, as shown in Figure 1.

In the embodiment of Figure 6, there is shown a similar stamp proper 11^a, except that the printing face 12^a is larger than that of the stamp proper 11 of Figures 3, 4, and 5. The parts of the stamp holder shown in this figure may be identical with those shown in Figure 4, except that the sleeve 25^a, which threadably engages the corresponding body 16^a as indicated at 26^a, has a correspondingly larger opening and smaller flange 27^a for overlapping the flange 14^a of the stamp 11^a. All of the other parts may be identical, that is, the body member 16^a, threaded extension 17^a, and nut 18^a, may be identical with the members 16 and 17 of the preceding embodiment.

The backing member 19^a and screw 22^a may be identical with the members 19 and 22 of the preceding embodiment, and even the resilient element 24^a may be identical with that designated as 24 in the preceding embodiment.

Reference to Figures 1 and 2 will show how a stamp embodying my invention may be used for etching or printing lamp bulbs, such as designated by the reference character 28. The stamp and holder are secured to an actuating member 29, as by screwing thereto the threaded extension 17 or 17^a, as the case may be. The total length is so adjusted that, when the machinery is operated, a proper amount of pressure is applied on the inner surface of the bulb 28, held in a head or other supporting device 31. The nut 18 or 18^a, as the case may be, is then tightened against the actuating member 29 to hold the stamp in adjusted position.

Before the member 29 is operated to print or etch the bulb 28, the stamp 11 is inked in any desired manner, as by means of an inking roller 32 on a movable arm 33 which carries said roller alternately to and from another roller 34 which transfers ink of the desired character thereto from a reservoir 35.

Before the inked stamp is brought into engagement with the bulb 28, a backing member 36, preferably carrying a concave resilient pad 37, is brought down upon the outer surface of the bulb to hold it in place, while the stamp is moved from the position indicated in dotted lines to that indicated in full lines in Figure 1.

After the inked stamp has printed on the bulb, as illustrated in Figure 1, it is withdrawn to the dotted position, the bulb removed, the stamp raised and re-inked as illustrated in Figure 2 and the bulb etching or stamping operation may be repeated.

Although I have shown my stamp as used with particular apparatus for etching or printing the inside surface of lamp bulbs, it will be understood that with suitable changes, such as substituting a correspondingly changed backing member 19, said stamp may serve for etching or printing the outer surfaces of lamp bulbs in a manner such as disclosed in any one of the Fredenburgh Patent #1,645,045, the Higgins et al. Patent #1,647,625, and the May Patent #1,647,646, all owned by the assignee of the present application. One form of glass printing or etching ink is disclosed in the Fredenburgh Patent #1,538,890, also owned by the assignee of the present application.

From the foregoing disclosure, it will be seen that I have provided an improved stamp and holder for etching or printing glass articles, such as bulbs for incandescent electric or other lamps, as well as a more satisfactory means for holding

such stamps in the manufacture of such devices, avoiding the former practice of cementing stamps to a hard rubber back before forwarding to the factory, which practice made it impossible to conveniently interchange stamps and holders, or use more than one stamp for a holder.

In accordance with my invention, the necessity for any cementing is eliminated, the requirement being merely that the stamp proper be forwarded to the factory for use with any holder.

On account of the use of a threaded sleeve for adjustably holding the stamps in place, not only is each stamp protected from injury by the inking roller, but provision is made for altering the curvature of the stamp face to one substantially spherical on a desired radius, by the pressure applied by the sleeve, predetermined by the extent to which it is screwed up on the body 16, whereby it may be made to accurately conform to the curvature of the surface to be etched or printed, so that perfect printing results are procurable without difficulty.

Although preferred embodiments of my invention have been disclosed, it will be understood that modifications may be made within the spirit and scope of the appended claims.

I claim:

1. A stamp device for printing comprising a holder, a backing member one side of which engages said holder, a resilient pad engaging the other side of said backing member, a rubber stamp engaging said pad, and means adjustably secured to said holder for clamping said stamp in engagement with said pad under predetermined pressure and curving said stamp to conform with the article to be printed.

2. A stamp device for printing comprising a holder having a body with a threaded extension for connection with operating means, a backing member one side of which engages said body, a resilient pad engaging the other side of said backing member, a rubber stamp engaging said pad, and means adjustably secured to said holder for clamping said stamp in engagement with said pad.

3. A stamp device for printing comprising a holder, a backing member, one side of which engages said holder and the other of which is convex to correspond with the curvature of the surface to be printed, a resilient pad engaging the other side of said backing member, a rubber stamp engaging said pad, and means adjustably secured to said holder for clamping said stamp in engagement with said pad.

4. A stamp for printing comprising a holder, a backing member one side of which engages said holder, a resilient pad engaging the other side of said backing member, a rubber stamp engaging said pad, and a sleeve threaded to said holder and having means for clamping said stamp in engagement with said pad under adjustable pressure.

5. A stamp device for printing comprising a holder a backing member one side of which engages said holder, a resilient pad engaging the other side of said backing member, a rubber stamp engaging said pad, and means having an inwardly projecting flange engaging the outer peripheral portion of said stamp to adjustably hold it in engagement with said pad.

6. A stamp device for printing comprising a holder, a backing member one side of which engages said holder, a resilient pad engaging the other side of said backing member, a rubber

stamp engaging said pad, and means adjustably secured to said holder for clamping said stamp in engagement with said pad under predetermined pressure, to distort it and the latter to curved form.

7. In a lamp bulb printing or etching device, a stamp device comprising a holder having a body with a threaded extension for connection with operating means, a backing member one side of which engages said body, and the other of which is convex to correspond with the curvature of the lamp surface to be engaged by the stamp, a sponge rubber pad engaging said convex surface, a rubber stamp engaging said pad, and a sleeve threaded to said body and having an inwardly projecting flange engaging an outer peripheral portion of said stamp, to adjustably hold it in position on said body and pull the stamp into compressing relation with said pad and distort it and the latter to convex form by pressing them over the convex surface of said backing member.

8. A stamp device for printing comprising a holder a backing member, one side of which engages said holder and the other of which is concave to correspond with the curvature of a convex surface to be printed, a resilient pad engaging the other side of said backing member, a rub-

ber stamp engaging said pad, and means adjustably secured to said holder for clamping said stamp in engagement with said pad to cause it to assume a desired printing surface curvature.

9. In lamp bulb printing or etching apparatus, a stamp device comprising a holder having a body with a threaded extension for connection with operating means, a backing member one side of which engages said body and the other of which is curved to correspond with the curvature of the lamp surface to be engaged by the stamp proper, a set screw passing through said body and threadably engaging said backing member to hold the latter seated in said body, a resilient pad engaging the curved surface of said backing member, a rubber stamp engaging the outer surface of said pad, said stamp comprising a central body portion formed with a stamping face and a relatively thin peripheral flange extending therefrom, and a sleeve member threadably adjustable on said body and having an inwardly projecting flange engaging the peripheral flange of said stamp, to adjustably hold it in position with respect to said pad and backing member, and distort it to a form corresponding with that of said lamp surface.

FREDERICK SAMUEL ROWE.
